INSULATED HAND BAG

Herbert Daust, St. Louis, Mo.

Application September 7, 1956, Serial No. 608,603

4 Claims. (Cl. 150—28)

This invention relates generally to improvements in a hand bag, and more particularly to a hand bag of a type adapted to carry articles for infant care, such as diapers and nursing bottles, when traveling or away from home.

An important object is realized in an improved construction of hand bags formed principally of flexible material with insulating interliners for the protection and temperature maintenance of articles disposed within the bag.

Another important objective is achieved by the provision of a pocket-forming assembly within the flexible covering of the bag, the assembly defining the shape and size of the pocket and serving to reinforce and maintain the shape of the hand bag.

Other important advantages are realized by disposing the pocket-forming assembly which includes a stiff panel and attached insulating layer within the flexible covering free from attachment to the covering or other element of the hand bag structure, such arrangement facilitating assembly of the bag and realizing more economical manufacture.

Still another important objective is afforded by the provision of stiff flanges attached to opposed lateral margins of the top opening in the covering, the stiff flanges extending internally of the bag between the lateral panel portions of the pocket-forming assembly and engaging such panel portions to prevent collapse of the assembly when a sack-like inner liner is extended out of the top opening for cleaning purposes and to assure reinsertion of the liner between the panel portions.

The foregoing and numerous other objects and advantages of the invention will more clearly appear from the following detailed description of a preferred embodiment, particularly when considered in connection with the accompanying drawing, in which:

Fig. 1 is a perspective view of a hand bag embodying the features of my invention;

Fig. 2 is a fragmentary, cross sectional view as seen along line 2—2 of Fig. 1;

Fig. 3 is a sectional view through a fragmentary end portion of the bag, as indicated by section line 3—3 of Fig. 1, and

Fig. 4 is a cross sectional view of the bag similar to Fig. 2, but showing the inner liner extended through the top opening for cleaning purposes.

The reference numeral 10 generally designates the hand bag which is seen to comprise a generally rectangular body having a carrying strap 11 attached to the top end portions thereof. The bag body is made up of an outer or covering envelope of fabric or plastic sheet material suitably cut and stitched to form sides 12 and 13 and integral bottom 14, and ends 15 and 16. The side and end members have their contiguous marginal portions inturned and stitched together, as indicated at 17 in Fig. 3.

The top of the bag is formed by the inwardly and downwardly turned upper margins of side panels 12 and

2

13, and by tape members 20 and 21 of a slide fastener or "zipper" type of closing unit indicated generally at 22. The attached margins of side panels 12 and 13 with tape members 20 and 21 constitute opposed lateral margins 23 of a top opening for the bag.

Normally located within the covering of the hand bag is an independent pocket-forming assembly generally indicated at 24 in Fig. 4. The pocket-forming assembly 24 consists of a substantially U-shaped panel 25 formed of a relatively stiff sheet material, the panel 25 including spaced opposed lateral panel portions 26 and integral lower bridging piece 27. Attached to the outer, surface of panel 25 is an insulating layer 30 of compressible fibre glass wool. The pocket-forming assembly 24, comprised of U-shaped panel 25 and attached insulating layer 30, is considered a separate independent element having no positive attachment to the flexible outer covering or any other element of the hand bag, the pocket-forming assembly 24 being insertable into the outer covering of the hand bag in a manner and for purposes which are hereinafter fully described.

The bag is provided with a sack-like inner liner 31 which is secured along its upper edge to the downwardly turned top margins of the side panels 12 and 13 and the fastener tapes 21 and 20. The liner 31 is otherwise unattached and hence it can be turned inside out by drawing it outwardly through the bag opening to expose the liner surface for cleaning and airing. The liner 31 includes a pair of moisture-resistant side portions 32, preferably formed of plastic sheeting, secured together along a longitudinal seam 33.

The pocket-forming assembly 24 is placed within the covering of the hand bag before seam 33 is closed. For example, with the zipper 22 open and with the seam 33 of liner portions 32 open, the pocket-forming assembly 24 is insertable between the liner portions 32, through the top opening of the bag and thence into the interior of the outer covering. It is possible to insert pocket-forming assembly 24 in this manner because the width of bridging panel piece 27 is slightly less than the width of the top opening of the bag and because the insulating layer 30 is highly compressible.

When disposed within the covering of the bag, the insulating layer 30 of the pocket-forming assembly is located between the outer flexible covering and stiff U-shaped panel 25. The panel portions 26 extend upwardly to the top of the bag closely adjacent the lateral margins of the top opening, and extend substantially to each end 15 and 16, thus the relatively stiff panel 25 serves to maintain the shape of the hand bag and in addition defines the shape and size of the pocket. It will be particularly noted that the pocket-forming assembly 25 is completely unattached to the covering or other element of the hand bag. The insulating layer 30 completely surrounds the pocket formed by stiff panel 25 except at each extreme end, and hence serves to maintain the temperature of articles disposed within such pocket.

Attached at each of the opposed lateral margins 23 of the top opening is a flange 34 comprised of relatively stiff sheet material, the flange 34 extending downwardly into the pocket formed by U-shaped panel 25. In the preferred construction, the flanges 34 extend substantially the length of the pocket. The flanges 34 extend downwardly to engage the lateral panel portions 26 and hence keep such panel portions 26 at the sides of the top opening, the advantages of which will appear later.

After the stiff flanges 34 are attached to the opposed lateral margins of the top opening, the seam 33 of sack-like liner 31 is closed by stitching and the liner inserted into the pocket formed by stiff panel 24, as is shown in Fig. 2. The liner 31 overlies the stiff flanges 34 and is

not attached thereto except at the upper end at the side margins 23 of the top opening.

Assuming for example that it is desired to clean the waterproof liner 31, the zipper 22 is opened and the liner 31 is drawn outwardly through the top opening, as is illustrated in Fig. 4. Because of the extremely flexible nature of the outer covering of the hand bag, the pocket-forming assembly 24 might collapse if it were not for the presence of stiff flanges 34. In other words, if flanges 34 were not present and if the sack-like liner 31 were extended, it might be possible for one or both of the panel portions 26 with its connected insulated layer 30 to move in a direction toward the other panel portion 26 and block the top opening of the bag. If this situation occurred, it is apparent that there would be no assurance that the sack-like liner 31 could or would be reinsertable into the pocket formed by stiff panel 25, but rather the liner 31 could be accidentally inserted into the covering at the side of one or the other of the lateral panel portions 26.

However, it will be noted that in the instant hand bag structure, when the liner 31 is extended out of the top opening, the stiff flanges 34 engage the stiff panel portions 26 and retain such panel portions at opposite sides of the top opening. Thus it is absolutely assured that the liner 31 after being aired and cleaned, will be repositioned into the pocket formed by stiff panel 25.

Although the invention has been described by making detailed reference to a single preferred embodiment, such detail is to be understood in an instructive, rather than in any restrictive sense, many variants being possible within the scope of the claims hereunto appended.

I claim as my invention:

1. A hand bag comprising an outer covering of pliable sheet material having a top opening and slide fastener means for closing said opening, a pocket assembly located within said covering, said pocket assembly including a pocket-forming panel of stiff sheet material, an insulating layer attached to the pocket-forming panel and located between the panel and said covering, flanges of stiff sheet material secured to the covering along opposed side margins of said top opening, said stiff flanges extending downwardly internally of the pocket forming panel, and a sack-like liner of flexible waterproof material secured to the covering at the margin of said opening and normally disposed internally of said pocket-forming panel in overlying relation to said stiff flanges.

2. A hand bag comprising an outer covering of pliable sheet material having a top opening and slide fastener means for closing said opening, a pocket assembly located within said covering, said pocket assembly including a pocket-forming panel of stiff sheet material having spaced lateral panel portions located at opposite sides of said top opening, an insulating layer attached to the pocket-forming panel and located between the panel and said covering, the stiff pocket-forming panel and insulating layer being free from attachment to said covering, flanges of stiff sheet material secured to the covering at opposed side margins of said top opening, said stiff flanges extending downwardly internally of the pocket-forming panel, and a sack-like liner of flexible waterproof material secured to the covering at the margin of said opening and normally disposed internally of said pocket-forming panel

in overlying relation to said stiff flanges, the liner being extensible out of the panel and top opening for cleaning, the stiff flanges engaging said lateral panel portions to prevent collapse of the pocket-forming panel and to assure reinsertion of the liner between the lateral panel portions.

3. A hand bag comprising an outer covering of pliable sheet material having a top opening and slide fastener means for closing said opening, a pocket assembly located within said covering, said pocket assembly including a substantially U-shaped pocket-forming panel of stiff sheet material, said panel having spaced lateral panel portions extending substantially the length of the bag and extending upwardly substantially to the top of the bag adjacent opposed side margins of said top opening, an insulating layer attached to the pocket-forming panel and located between the panel and said covering, flanges of stiff sheet material secured to the covering along opposed side margins of said top opening, said stiff flanges extending downwardly internally of the U-shaped pocket-forming panel, and a sack-like liner of flexible waterproof material secured to the covering at the margin of said opening and normally disposed internally of said pocket-forming panel in overlying relation to said stiff flanges, the liner being extensible out of the top opening for cleaning, the stiff flanges engaging said lateral panel portions to prevent collapse of the U-shaped pocket-forming panel and to assure the insertion of the liner between the lateral panel portions, the U-shaped pocket-forming panel and insulating layer being free from attachment to said covering.

4. A hand bag comprising an outer covering of pliable sheet material having a top opening and slide fastener means for closing said opening, a pocket assembly located within said covering, said pocket assembly including a pocket-forming panel of stiff sheet material having spaced lateral panel portions located at opposite sides of the said top opening, an insulating layer attached to the pocket-forming panel and located between the panel and said covering, flanges of stiff sheet material secured to the covering along opposed side margins of said top opening, said stiff flanges extending downwardly internally of the pocket-forming panel, and a sack-like liner of flexible waterproof material secured to the covering at the margin of said opening, said liner having a seam through which the pocket-forming assembly of panel and insulating layer is inserted into the covering before seam closure, the stiff pocket-forming panel and insulating layer being free from attachment to said covering, said liner being normally disposed internally of said pocket-forming panel in overlying relation to said stiff flanges, and being extensible out of the top opening for cleaning purposes.
